DESIGN FOR CANDY

Clarence Dickinson Reed, Chicago, Ill., assignor to Reed Candy Company, Chicago, Ill., a corporation of Illinois

Application May 26, 1934, Serial No. 51,937

Term of patent 14 years

To all whom it may concern:

Be it known that I, CLARENCE DICKINSON REED, a citizen of the United States, residing at Chicago, in the county of Cook and State of Illinois, United States of America, have invented a new, original, and ornamental Design for Candy, customarily referred to as lolly pops, or candy suckers, of which the following is a specification, reference being had to the accompanying drawing, forming a part thereof:

Fig. 1 is a plan view of a piece of candy constituting my design;

Fig. 3 is a cross sectional view thereof taken on the lines B—B of Figure 1.

The candy is substantially the form or shape of a heart, the inner part being depressed or sunken in heart shape, said depressed or sunken portion being formed on both sides of the candy with a raised outer edge extending entirely around the sunken part on both sides.

I claim:

The ornamental design for candy, as shown and described.

CLARENCE DICKINSON REED.
